T. J. Sloan

THOMAS J. SLOAN, OF NEW YORK, N. Y.

Letters Patent No. 88,918, dated April 13, 1869.

IMPROVEMENT IN SECURING KNOBS TO THEIR SHANKS.

The Schedule referred to in these Letters Patent and making part of the same.

To all whom it may concern:

Be it known that I, THOMAS J. SLOAN, of the city, county, and State of New York, have invented a new and useful Improvement in Securing Metallic Shanks to Door-Knobs made of porcelain and other earthenware; and I do hereby declare that the following is a full, clear, and exact description thereof, reference being had to the accompanying drawings, making part of this specification, in which—

Figure 1 is an elevation of a knob, with a metal shank secured thereto;

Figure 2, a section taken in the plane of the axis of the shank;

Figure 3, a section taken in the plane of the line A a of fig. 2; and

Figure 4, the several parts represented separately.

My said invention relates to an improvement in the method of securing metallic shanks to knobs made of porcelain and other earthenware.

Metallic shanks have heretofore been secured in such knobs by soft metal, which melts at a sufficiently low temperature to be run into the cavity of the knob and around the hard-metal shank, or which is sufficiently ductile to admit of being packed into the cavity to secure the hard-metal shank.

Experience has proved that these methods are defective, because in use the soft metal soon yields, and the knob becomes loose.

The object of my invention is to effect a more solid and durable connection between the knob and the shank; and to this end.

My said invention consists in so forming the cavity in the knob, that a hard-metal plate can be readily inserted, so that when partly turned at the bottom of the cavity portions of the plate will pass into lateral cavities or under projections, so that it cannot be drawn out, and connecting one end of a screw with the said plate, so that the screw cannot be drawn out except with the plate, and by first turning the plate, and combining with the knob, plate, and screw, a shank having a threaded cavity at one end to fit the screw held by the plate within the cavity of the knob.

Having thus pointed out the principle or character of my said invention, I will particularly describe, by reference to the accompanying drawings, the mode of construction which I deem the best.

I form the knob a, either in the act of moulding or afterwards, with a cavity, b, to receive the inner end of the metallic shank c, and I prefer to make this part

of the shank with two angular wings or feathers, d d, one on each of two opposite sides, the cavity in the knob being of a form suitable to receive the said wings or feathers.

At the bottom of the cavity, the recesses e e, which receive the feathers d d of the shank, are extended for a short distance around, forming two grooves, f, one on each side, as represented.

A plate of hard metal, g, of a form which will readily enter the cavity b of the knob, and with two wings i i is formed with a central hole to receive the shank of a screw, h, having a flat head below the plate.

The shank of this screw is threaded to fit and screw into the bore of the inner end of the shank c, and the outward extremity is nicked, as at l, to receive a screw-driver, or otherwise formed, so that it can be turned by a driver or key to be inserted in the tubular shank from the other end.

The parts being so formed, the plate g, with the screw h is inserted in the cavity of the knob with the head of the screw towards the bottom of the cavity, and when the plate reaches the bottom, it is turned until its wings i i, are carried into the lateral grooves f.

In that position the plate is secured so that it cannot be drawn out, and by that means the screw is held in the cavity, but free to turn. The shank is then applied to the cavity and to the end of the screw, and, by inserting a screw-driver through the shank and turning the screw, the shank is drawn into the cavity of the knob and there secured, so that it can neither turn nor become loose, except by turning the screw in the opposite direction.

If desired, the screw can be permanently secured to the plate g, and the shank made round, so that it can be turned on the screw until drawn home to its place in the cavity of the knob, and there keyed to prevent turning. But the mode of construction first above described I consider the best.

What I claim as my invention, and desire to secure by Letters Patent, is—

Forming the cavity in the knob with lateral grooves or recesses, to receive and hold the ends of the locking-plate, in combination with the said locking-plate, screw held by the locking-plate and the hollow shank, substantially as and for the purpose described.

THOS. J. SLOAN.
